UNITED STATES PATENT OFFICE

107,841

DESIGN FOR A DRESS ENSEMBLE

Jack Kirschner, New York, N. Y.

Application July 30, 1937, Serial No. 70,733

Term of patent 3½ years

To all whom it may concern:

Be it known that I, Jack Kirschner, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

I claim:

The ornamental design for a dress ensemble, substantially as shown.

JACK KIRSCHNER.
